(57) CLAIM

The ornamental design for a tea press, as shown and described.

DESCRIPTION

FIG. 1 is a perspective view of a tea press showing our new design in its closed position where the bottom portion is a drip sheath, and the infuser, shown in FIGS. 2 and 3, mates with the drip sheath and the plunger mates with the infuser;

FIG. 2 is a side elevational view of a tea press in its open position where the drip sheath has been removed for ease of illustration and the plunger has been unmated with the infuser to its extended position;

FIG. 3 is an exploded perspective view of the tea press showing the drop sheath, the infuser, and the barrel, with the plunger, syringe and cap removed for ease of illustration; and, FIG. 4 is an exploded perspective view of a tea press showing the syringe and cap with the rest of the parts removed for ease of illustration.
